UNITED STATES PATENT OFFICE.

EDWARD C. CLARK, OF NUTLEY, NEW JERSEY.

GRATE-BAR.

1,145,349.

Specification of Letters Patent.

Patented July 6, 1915.

Application filed October 10, 1912. Serial No. 724,907.

To all whom it may concern:

Be it known that I, EDWARD C. CLARK, a citizen of the United States, residing at Nutley, in the county of Essex and State of New Jersey, have invented certain Improvements in Grate-Bars, of which the following is a specification.

This invention relates more particularly to that class of grate bars which are employed in chain grates, such as are found in mechanical stokers, and the objects of the invention are to provide such a grate bar with improved means for attaching the same to the chains; to provide such means which shall hold the bar rigidly with respect to the links engaged by the attaching means; to provide such means which shall detachably connect the grate bar to the chains; to provide new and improved means for connecting the grate bar to the horizontal links of the chains; to provide attaching means which shall partly encircle a horizontal link; to enable said attaching means to be disengaged by being brought opposite a vertical link; to connect such attaching means firmly and securely to the grate bar; to secure simplicity of construction, and to obtain other advantages and results as may be brought out in the following description.

Referring to the accompanying drawings in which like numerals of reference indicate the same parts throughout several views, Figure 1 is a side elevation of my improved grate bar; Fig. 2 is a plan of the same; Fig. 3 is a vertical longitudinal section taken on line A—A of Fig. 2; Fig. 4 is an inside view of one of the side pieces detached; Fig. 5 is an end view of the grate bar as seen from the right-hand end of Fig. 1; Fig. 6 is an enlarged sectional view of a certain shoe for supporting said end of the grate bar upon its chain; Fig. 7 is a perspective view of one of the transverse members removed from the bar; Fig. 8 is a sectional view on line B—B of Fig. 3, looking in the direction of the arrows, and Fig. 9 is a similar sectional view taken on line C—C of Fig. 3.

In the specific embodiment of the invention illustrated in said drawings, the grate bar has a body portion 1 made up of two longitudinal side pieces 2, 3, spaced apart from each other, said body portion removably supporting upon itself a plurality of transverse members which constitute in practice the floor of the fire-box. With more

particular reference to Fig. 4, wherein is shown the inside face of one of the said side pieces 2, a plurality of spacing ribs 4, 4, preferably disposed longitudinally of the side piece in staggered relation to each other, are integrally formed on the side piece 2, whereby the side pieces are spaced apart and a circulation of air is admitted between them. The second side piece 3 above referred to is likewise provided with spacing ribs 5, 5 preferably parallel to and spaced transversely from the rib 3, 3 of the first said bar 2 when the said side pieces are assembled. Rivets or the like 6, 6 extending between the side pieces 2, 3 clamp the same rigidly in the spaced relation established by the said ribs 4, 5.

It will be noted that the ribs 4, 5 protect the rivets 6 from the heat above and below and yet allow circulation longitudinally of the bar. Furthermore, it will be understood that by the said ribs 4, 5 arranged one on each of the side pieces 2, 3, each side piece can be put in a planer and the ends or edges of its ribs planed down to a standard, so that when the two side pieces are put together the ribs of each will contact firmly against the other.

At one end of the grate bar and preferably riveted between the two side pieces 2, 3 is a depending hook 7 adapted to engage in a vertical link 8 of the stoker chain as usually employed. The opposite end of the bar is provided with a pair of upwardly converging flanges 9, 10 one of which, as 9, is integral with the first mentioned side-piece 2, as seen in Fig. 4, whereas the other flange 10 is integral with the other side piece 3. A pocket is thereby provided in which is supported by means of a rivet 11 or the like passing transversely through the side-pieces 2, 3, a shoe 12, by means of which the grate bar is secured to the chain or a horizontal link 13 thereof. This shoe has a pair of opposite hooked arms 14, 14 depending from the body portion 1 of the grate bar and adapted to grasp between themselves the link 13 as shown in Fig. 3. These hooked arms 14, 14 are clamped rigidly to the link by a bolt 15 between the two arms tending to draw them together, so that the grate bar may be located in spaced relation to the adjacent grate bars. Obviously, when this bolt 15 is loosened the hooked arms can be slid to one end of the horizontal link and

then disengaged entirely from the chain while opposite the vertical link.

The upper longitudinal portion of each of the side pieces 2, 3 preferably flares outwardly upward, as shown in Figs. 8 and 9 for example, so as to make the body portion of the grate bar wedge-shaped in cross-section at its upper part. Each of the transverse members 16 comprises a plate-like body having at the middle of its lower edge a recess 17 (see Fig. 7), the sides 18, 18 of said recess converging downwardly to conform with the wedge-shape of the body portion 1 just described, whereby a dovetail joint is secured between said body portion and the transverse members 16. Thus the only movement permitted the transverse members is longitudinally of the grate bar, their insertion and removal being effected at the end of the body portion. Each transverse member is at its upper edge preferably leveled from the middle to its ends, and at its lower edge rounded or curved from the recess 17 to said ends, so as to provide projections or fingers 19 along the side of the grate bar. These projections or fingers are spaced by lugs 20 upon the opposite sides of the transverse member, there being two lugs on each side of the member arranged one on the lower inner part of each lateral projection so that the recess 17 is between them. These lugs are integrally formed with the transverse member and butt against similar lugs on the next adjacent transverse member, when said members are assembled on the body portion of the grate bar, thereby securing spaces between the lateral projections along the sides of the grate bar. Although it is preferable to make the transverse members of separate pieces of material throughout the middle portion of the grate bar, as shown, yet next adjacent the ends of said bar where the heat from the fire is less intense, the transverse members may be integrally constructed in a series or block 21. Longitudinal displacement of the transverse members from the grate bar, when assembled, is prevented by means of end plates 22, 22 or other equivalent means suitably secured to the ends of the body portion 1.

Obviously the circulation of air which is permitted between the side pieces 2, 3 is likewise free to pass upward between the transverse members 16, and such upward circulation is preferably facilitated by hollowing out the transverse members each at the middle of its upper edge, as at 23, 23, so that the air may pass upward therethrough. This circulation of air not only keeps the side pieces 2, 3 and the transverse members cool, but also affords a better draft for the fire. Furthermore a greater surface for radiation of heat from the grate bar is provided by constructing the same in this man-

ner, all of which advantages tend to prevent warping of the bar and secure free action of the grate.

It will be noted, also, that should one of the transverse members become broken, it is necessary only to remove one of the end plates 22, slide off the block or series 21 and the members 16 up to the broken one, which may then be replaced by a new member and the others then put back again.

It will be noted that each transverse member 16 may have a tongue 28 depending into the upper part of its recess 17 and adapted to enter between the side-pieces 2, 3, when the transverse members are slid thereinto, as clearly shown in the drawing. I do not, however, restrict myself to the use of this tongue, and there are various other modifications in detail construction which can be made by those skilled in the art without departing from the spirit and scope of the invention.

Having thus described the invention, what I claim is:

1. The combination with a grate bar and means at one end thereof adapted to secure it to a chain, of a shoe at the other end of said grate bar having arms projecting downward therefrom in a plane longitudinal of the grate bar, said arms having hooked ends directed inwardly toward each other and adapted to grasp between themselves a chain lying transversely of the grate bar beneath the same, and clamping means adapted to hold said hooked arms in engagement with such a chain.

2. The combination with a grate bar and means at one end thereof adapted to secure it to a chain, of a shoe at the opposite end of said grate bar having arms arranged in alignment with each other longitudinally of the grate bar, said arms having hooked ends directed inwardly toward each other and adapted to receive between themselves a horizontally disposed chain link lying transversely of the grate bar beneath the same, and clamping means adapted to hold said hooked arms in engagement with such a link.

3. The combination with a grate bar having a body portion with longitudinal side-pieces secured together, of a shoe secured between said side-pieces at one end of the body portion and having arms projecting downward therefrom in a plane between said side-pieces and said arms having hooked ends directed inwardly toward each other and adapted to grasp between themselves a horizontally disposed chain link lying transversely of the grate-bar beneath the same, and means adapted to hold said hooked arms in engagement with such a link.

4. The combination with a grate bar having a body portion with side-pieces provided near one end and at their inner faces with

upwardly converging transverse flanges, of a shoe comprising hooked arms having their upper ends secured to the side-pieces between the said flanges thereof and their lower ends projecting below said side-pieces and having hooks directed toward each other and adapted to receive a chain between themselves.

5. The combination with a grate bar having a body portion with longitudinal side-pieces secured together, of a shoe secured between said side-pieces at one end of the body portion and having arms arranged in alinement with each other longitudinally 10 of the grate bar, the lower ends of said arms being spaced from each other and provided with hooks directed inwardly toward each other and adapted to receive between themselves a chain, and means for adjustably clamping said hooks together.

6. The combination of a grate bar having a body portion with longitudinal side-pieces secured together, said side-pieces having at their inner faces upwardly converging flanges in spaced relation longitudinally of the grate bar, of a shoe having downwardly diverging arms arranged in the plane of the grate bar and engaging the said converging flanges, the lower ends of 25 said arms being spaced apart longitudinally of the grate bar and having hooks projecting toward each other and adapted to receive between themselves a chain, and means for fastening the shoe to the grate bar.

35. 7. In an endless chain grate the combination of a chain having horizontal and vertical links, a grate bar, and means for detachably connecting the grate bar to the chain, said means comprising members 40 formed to partly encircle and to engage a horizontal link of the chain and to be disengaged from the chain when brought opposite to a vertical link thereof.

8. In an endless chain grate the combination 45 of a chain having horizontal and vertical links, a grate bar, a shoe for detachably connecting the grate bar to the chain, said shoe having members formed to partly encircle and to engage a horizontal link of the chain and to be disengaged from the chain when opposite to a vertical link thereof, and means for locating the grate 50 bar in spaced relation to adjacent grate bars.

55. 9. The combination with a grate bar and means at one end thereof adapted to secure it to a chain, of a shoe at the other end of said grate bar having arms projecting downward therefrom in a plane longitudinal of the grate bar, said arms having hooked ends directed inwardly toward each other and adapted to grasp between themselves a chain lying transversely of the grate bar beneath the same.

60. 10. The combination with a grate bar and

means at one end thereof adapted to secure it to a chain, of a shoe at the opposite end of said grate bar having arms arranged in a line with each other longitudinally of the grate bar, said arms having hooked ends 70 directed inwardly toward each other and adapted to receive between themselves a horizontally disposed chain link lying transversely of the grate bar beneath the same.

11. The combination with a grate bar and means at one end thereof adapted to secure it to a chain, of a shoe at the other end of said grate bar having arms projecting downward therefrom with hooked ends 75 directed inwardly toward each other and adapted to grasp between themselves a horizontally disposed link of a chain and to disengage from the chain when brought opposite a vertical link thereof.

12. The combination with a grate bar and means at one end thereof adapted to secure it to a chain, of a shoe at the other end of said grate bar having arms projecting downward therefrom with hooked ends 80 directed inwardly toward each other and adapted to grasp between themselves a horizontal link of a chain and to disengage from said chain when brought opposite a vertical link thereof, and means for locating the 85 grate bar in spaced relation to adjacent grate bars.

13. The combination with a grate bar having a downwardly opening recess near one end and means at the other end adapted to secure it to a chain, of a shoe seated at its upper end in said recess and having arms projecting downward therefrom with hooked ends directed inwardly toward each other and adapted to grasp between themselves a chain lying transversely of the 90 grate bar beneath the same.

14. The combination with a grate bar having a downwardly opening recess near one end and means at the other end adapted to secure it to a chain, of a shoe seated at its upper end in said recess and having arms projecting downward therefrom with hooked ends directed inwardly toward each other and adapted to grasp between themselves a chain lying transversely of the 95 grate bar beneath the same, and means for securing said shoe in said recess.

15. The combination with a grate bar having near one end a downwardly opening 100 recess with one end wall inclined downwardly outward and means at the other end of the grate bar adapted to secure it to a chain, of a shoe having its upper end seated in said recess and beveled at one edge to 105 engage said incline, said shoe having arms projecting downward with hooked ends directed inwardly toward each other and adapted to grasp between themselves a 110 chain.

4

16. The combination with a grate bar having near one end a downwardly opening recess with one end wall inclined downwardly outward and means at the other end 5 of the grate bar adapted to secure it to a chain, of a shoe having its upper end seated in said recess and beveled at one edge to engage said incline, said shoe having arms projecting downward with hooked 10 ends directed inwardly toward each other and adapted to grasp between themselves a chain, and means for securing said shoe in said recess.

17. In an endless chain grate, the combi-

nation of a chain having horizontal and 15 vertical links, a grate bar, and means for detachably connecting the grate bar to the chain, said means comprising members with hooked ends adapted to grasp between themselves a horizontal link of a chain and 20 providing space between themselves for a vertical link of the chain, whereby said means can be detached from the chain when brought opposite to a vertical link thereof.
